UNITED STATES PATENT OFFICE.

LEGRAND B. ROLPH, OF WINDOM, MINNESOTA.

WEATHER-STRIP FOR DOORS.

SPECIFICATION forming part of Letters Patent No. 723,029, dated March 17, 1903.

Application filed June 17, 1902. Serial No. 112,066. (No model.)

To all whom it may concern:

Be it known that I, LEGRAND B. ROLPH, a citizen of the United States, residing at Windom, in the county of Cottonwood and State 5 of Minnesota, have invented new and useful Improvements in Weather-Strips for Doors, of which the following is a specification.

This invention relates to weather-strips for doors, and more particularly to a trip therefor.

The object of the invention is to provide means whereby a horizontally-arranged hinged weather-strip secured to the jamb of a door will be automatically raised to close 15 the crack at the bottom of the door when the door is closed.

Further objects, as well as the novel details of construction, will be specifically described hereinafter and illustrated in the accompanying drawings, in which—

Figure 1 is a perspective view of the door and frame, the door being open. Fig. 2 is a horizontal sectional view on the line 2 2, Fig. 4. Fig. 3 is a detail perspective view of the 25 lower portion of the door, showing the weather-strip and trip attached. Fig. 4 is an elevation of the door closed. Fig. 5 is a vertical longitudinal sectional view through the door and frame, and Fig. 6 is a detail perspective 30 view of the trip.

The reference-numeral 1 designates a door-frame, and 2 the door, which is hinged thereto in the usual manner. Secured to the sill of the door-frame is a laterally-arranged 35 hinged weather-strip 3, the edge nearest the door being adapted to swing upward when the door is closed. A rigid strip 4 is secured to the door 2 and is inclined downward at an angle of about forty-five degrees. Immediately below the door, but spaced apart, are 40 projections 5, between which and the strip 4 the weather-strip 3 is adapted to be guided when the door is closed.

Arranged on the jamb of the frame 1 and 45 at one side thereof is the trip, which consists of a horizontal plate 6, having its lower end bent to form a barrel 7 for the reception of a pintle 8, (shown in dotted lines, Fig. 6,) which passes therethrough and is provided with a

right-angular projection terminating in a 50 right-angular point 9, which may be driven into the sill, so that the plate may be hinged. A vertical flange 10 projects from one side of the plate 6 and carries an inclined lip 11 at the rear extremity thereof, which projects 55 between the rabbet 12 in the door-frame 1 and the rear edge of the door 2. The plate 6 lies under the hinged weather-strip and as the door is closed the rear edge thereof will press against the lip 11 and force it in a vertical plane into the rabbet of the door-frame. This will cause the plate 6 to be tilted and raise the weather-strip, guiding it between the projections 5 and the rigid plate or strip 4 on the door. As the edge of the hinged 65 weather-strip is guided between the rigid strip of the door and the projections, a tight joint will be made, which will prevent the admittance of dust, rain, or any matter detrimental to the interior of the building. 70

I am aware that hinged weather-strips have been employed before and that trips have been used for the purpose of operating them; but I am not aware that a device similar to the one constructed by me has been employed 75 in combination with the elements to operate it.

By arranging the flange 10 on a vertical plane and constructing the plate 6 and lip 11 integral therewith a cheap, durable, and efficient trip is provided well adapted to withstand the strain to which it would be subjected in opening and closing the door. By operating the weather-strip 3 by means of this trip the liability of the weather-strip becoming fast through freezing will be obviated. 85

Having thus fully described my invention, what I claim, and desire to secure by Letters Patent, is—

The combination with a door-frame and a 90 hinged door secured thereto, of a hinged weather-strip secured to the sill of the frame and having its free end adjacent the door, a rigid strip secured to the door above on a higher plane than the weather-strip and projecting on a downward incline, projections beneath the strip on the door and designed to guide the weather-strip against the lower 95

side of the strip on the door, and a trip for raising the weather-strip and guiding it between the strip and comprising a horizontal plate having its lower end bent to form a hinge-barrel, a pintle in the barrel and secured to the door-sill, a vertical flange formed with and projecting from the plate, an inclined lip at the extremity of the vertical

plate and projecting from the door-frame and door for the purpose set forth. 10

In testimony whereof I affix my signature in presence of two witnesses.

LEGRAND B. ROLPH.
